UNITED STATES PATENT OFFICE

ALFRED FREED, OF CHICAGO, ILLINOIS

DESIGN FOR A BOX

Application filed October 23, 1929. Serial No. 33,142. Term of patent 3½ years.

To all whom it may concern:

Be it known that I, ALFRED FREED, a citizen of the United States, residing at 921 Eastwood Avenue, in the city of Chicago, county of Cook, and State of Illinois, have invented a new, original, and ornamental Design for Boxes, of which the following is a specification, reference being had to the accompanying drawing, forming part thereof, in which:

Fig. 1 is a plan view of a box showing my new design.

Fig. 2 is a side elevation.

Fig. 3 is an inverted plan view.

Fig. 4 is a perspective view.

Fig. 5 is a side elevation, the box having been rotated 45° on a horizontal plane from the position shown in Fig. 2.

I claim:

The ornamental design for a box as shown. Oct. 21st, 1929.

ALFRED FREED.
